MECHANICAL LOOPER

Henry F. Webster, St. Louis, Mo.

Application June 21, 1933, Serial No. 676,791

4 Claims. (Cl. 112—80)

The invention relates to the art of forming a series of loops of yarn or narrow strips of material particularly as used in forming hooked rugs in which the material is projected through and withdrawn from a backing fabric of burlap or the like so as to form a plurality of closely spaced loops of material projecting from one side of the fabric, which loops may be cut subsequently and brushed to form a thick pile.

Ordinarily, work of this kind is done by manually inserting a yarn or strip-threaded needle through the fabric then, by a separate manual operation, thrusting a loop holding element through the fabric then, by a separate manual operation, withdrawing the needle, stepping it along the fabric and again inserting it and then, by a separate manual operation, withdrawing the loop holding element and stepping it along the fabric and again projecting it through the latter to engage the next loop.

It has been proposed to provide a mechanical driving mechanism for reciprocating the feed point and loop point through the backing, but, so far as I am aware, the operation of such devices has resulted in uneven lengths and spacing of loops and in a loose yarn or fabric at the rear of the backing.

The object of the present invention is to provide a simple, efficient, mechanical device for the purpose indicated above, which device will form a plurality of even loops on one side of the backing and will draw the yarn or material tight at the rear of the backing and will insure even spacing of the successive loops and will discharge these functions with a minimum amount of skill or attention by the operator. This object is attained generally by providing an intermittent driving mechanism for each of the points whereby each point will remain stationary, in a position in which it is projected through the work, throughout the withdrawing, stepping forward, and reinsertion of the other point.

As will be more clearly apparent from the following description and the accompanying drawing, such a mechanism attains the desired object, and in the accompanying drawing—

Figure 1 is a rear view of the tool.

Figure 2 is a side view of the same, portions being broken away and sectioned to more clearly illustrate the construction.

Figures 3, 4 and 5 are views of upper and lower parts shown in Figure 2 (the intermediate portions being omitted) but showing them in successive related positions assumed during the cycle of operations of the tool.

A flat bar 1 forms the frame of the device and is offset at its upper end and provided with a rigid handle 2 by which the device is held by the operator. Mutilated gears 3 and 4 are mounted on opposite sides of frame 1, being journaled about a common axis A and in fixed relation to each other, the teeth 5 of gear 3 being opposite the mutilated portion 6 of gear 4 and the teeth 7 of gear 4 being opposite the mutilated portion 8 of gear 3. A crank and handle 9 comprises means for rotating gears 3 and 4.

Individual pinions 10 and 11 are mounted on opposite sides of frame 1, being relatively rotatable and in operative association with gears 3 and 4, respectively. The ratio of gears 3 and 4 to pinions 10 and 11 is as two to one. Two teeth 12 of pinion 10 are shorter than the remaining teeth and can oppose the mutilated portion 8 of gear 3 to hold pinion 10 against rotation during the movement of the mutilated portion 8 past the pinion. Pinion 11 is similarly constructed and locked in stationary position during the passage of mutilated portion 6 of gear 4 past the pinion 11. Each pinion carries a crank 13 and 14, respectively, and links 15 and 16 depend from cranks 13 and 14 and may be reciprocated thereby.

Guides 17 and 18 are secured to frame 1 and channel shaped bars 19 and 20, respectively, are slidable in guides 17 and 18. Bar 19 is narrower than bar 20 and is nested therein. Clips 21 and 22 secure the lower ends of links 15 and 16, respectively, to bars 19 and 20. A screw 23 adjustably mounts the needle or feed point 24 on the lower end of bar 19 and a screw 25 adjustably mounts the looper point 26 on the lower end of bar 20. Bars 19 and 20 are provided with ring-like stops 27 and 28, respectively, which are shaped to engage the material on which the device is operating over a substantial area without seriously interfering with the vision of the operator if he is endeavoring to follow a pattern stamped on the material.

Operation.—In Figures 1 and 2 the device is in a position which may be considered as the beginning of a cycle of operations although several previously formed loops L are indicated. The feed point 24 is projected through the backing B with its stop 27 engaging the latter. (At the beginning of the job, the entire device would be moved bodily to thrust point 24 to the position shown.) The yarn Y extends from the eye E of the feed point through the opening in stop 27 and may be drawn freely through the stop ring without being caught or pinched between the stop and the material.

- The teeth 7 of gear 4 are enmesh with the teeth of pinion 11 and rotation of crank handle 9—90° in a clockwise direction, to the position shown in Figure 3, rotates pinion 11—180° so that its crank 14 is in the reverse of the position shown in Figure 1 and the looper point 26 moves downwardly into the loop of yarn L' just formed by the feed point, drawing the yarn at the rear of the point tight against the backing and also drawing in additional yarn through the opening in stop 27 so as to lengthen the loop. Stop 28 governs the position of the looper point relative to the backing and serves as a clamp engaging the yarn at the rear of the points to resist movement of the same and the shortening of previously formed loops. During this movement of the looper point the feed point remains stationary as the last half of the mutilated portion 8 of gear 3 is riding over the short teeth 12 of pinion 10.
- During the next 90° movement of crank 9, the first half of the mutilated portion of gear 4 rides over the short teeth of pinion 11, holding the latter, its crank 14, link 16 and the looper point 26 stationary and at the same time the teeth 5 of gear 3, being enmesh with the teeth of pinion 10, rotates the latter and its crank 13 to raise the feed point to the position shown in Figure 4. It will be noted that the feed point 24 and looper point 26 are inclined downwardly and to the right so that as feed point 24 is withdrawn from the backing it moves forwardly, as indicated at X, Figure 3, so that upon again being projected downwardly it will pierce the backing at a point spaced from the previous loop.
- Upon further 90° movement of crank 9, feed point 24 is thrust downwardly through the backing to the position shown in Figure 4, carrying with it the yarn Y. During this movement the looper point 26 has remained stationary, holding the loop in the position shown and, accordingly, the feed point has drawn the yarn downwardly so as to tightly engage the piece of backing between the two loops.
- Upon further 90° movement of the crank 9, the looper point 26 is withdrawn from the previous loop and upon passing above the backing, moves forwardly and the parts are in the same relative position as indicated in Figures 1 and 2, the cycle of operations of the device having been completed.
- From the above description, it will be seen that one of the points is in each loop from the time the loop is first formed until the succeeding loop is formed. In other words, the feed point remains in the loop until the looper point is inserted therein and the looper point remains in the loop until the feed point descends to form the next loop. So long as either of the guards 27 or 28 is maintained in contact with the backing, one of the points will be holding the loop and the loops will be formed of uniform length and the portion of the yarn at the rear of the backing will be maintained tight against the same.
- The device will feed itself automatically along the line of stitching, although an experienced operator will be able to increase or decrease the distance between successive stitches or loops by inclining the tool from the vertical.
- In addition to the formation of the loops more evenly and tighter than is likely to be attained by tools in which the points are actuated in both directions by alternate movements of the opera-

tor's hands, the use of my novel device makes possible a much greater speed of looping than would be otherwise obtained.

Obviously, the details of construction may be substantially varied without departing from the spirit of the invention and I contemplate the exclusive use of any modifications in the structure as come within the scope of my claims.

What is claimed is:

1. In a device of the class described, a frame, a handle by which said frame may be held in the desired position, a hand operated crank journaled on said frame, a needle point and a looper point slidably mounted on said frame, means operated by continuous rotation of said crank for reciprocating said points alternately and holding each point in projected position while the other point is being reciprocated, and ring-like elements associated with said points for engaging the fabric being worked to hold the device in desired relation thereto irrespective of the reciprocation of said points, the ring-like element associated with the needle point being constructed and arranged to receive the yarn supplied to the needle point.

2. In a device of the class described, a frame member, mutilated driving gears journaled on said frame member, corresponding driven pinions associated with said gears and having continuous teeth, the tooth portion of one of said gears co-acting with teeth of the corresponding pinion to drive the latter while the mutilated portion of the other of said gears is co-acting with teeth of its corresponding pinion to lock the latter against rotation and vice versa, and a feed point and a looper point slidably mounted on said frame and reciprocated respectively by said pinions.

3. In a device of the class described, a frame, a toothed pinion journaled thereon with a portion of its teeth being shortened, a mutilated gear journaled on said frame with its teeth arranged to mesh with all the teeth of said pinion and with its mutilated portion arranged to co-act with the end of said shortened pinion tooth portion to hold said pinion against rotation temporarily, a crank on said pinion and a feed point reciprocated by said crank intermittently, said feed point being in advanced position when said pinion is held against rotation as described, another similar pinion, gear and crank mechanism, a looper point similarly reciprocated thereby, and means timing the operation of said mechanisms alternately.

4. A loop stitch forming device of the class described comprising a needle point and a looper point, individual elements associated with said points and extending laterally therefrom, mechanical means for withdrawing said needle point from the material and again thrusting it through the material while the looper point element engages the work to hold the looper point stationary, continued operation of said mechanical means then withdrawing said looper point and its element from the material and again thrusting it through the material while the needle point element engages the work to hold the needle point stationary, the element on said needle point being of ring-like formation to receive the yarn supplied to the needle point and to facilitate inspection of the path of the device.
